UNITED STATES PATENT OFFICE.

GEORGE A. FORD, OF CLEVELAND, OHIO.

CLAMP FOR SUPPORTING TACKLE-BLOCK STRAPS WHILE RIVETING THE SAME.

SPECIFICATION forming part of Letters Patent No. 391,409, dated October 23, 1888.

Application filed June 21, 1888. Serial No. 277,719. (No model.)

To all whom it may concern:

Be it known that I, GEORGE A. FORD, of Cleveland, in the county of Cuyahoga and State of Ohio, have invented certain new and useful 5 Improvements in Tackle-Blocks; and I do hereby declare the following to be a full, clear, and exact description of the invention, such as will enable others skilled in the art to which it pertains to make and use the same.

10 My invention relates to an apparatus for riveting the tackle-block shell described in United States Letters Patent No. 368,144, granted to me August 9, 1887.

In the accompanying drawings, Figure 1 is 15 a plan partly in section. Fig. 2 is an elevation in section on the line xx , Fig. 1. Fig. 3 is an elevation, partly in section, on the line yy , Fig. 1. Fig. 4 is a view in perspective of 20 an end portion of a tackle-block casing, portions being broken away to show the construction. Fig. 5 is an inside end elevation of the riveting-blocks in their relative position to each other, and Fig. 6 is a side elevation of the same. Fig. 7 is a plan of the wedge. Fig. 8 is a view 25 in perspective of a center-piece for double block.

A represents the cheek-pieces of the tackle-block, the same being flanged, as shown at a , a' , and a'' . B B are the draft-straps, and C C' 30 are the external and internal plates that hold the cheek-pieces in place, the plates and cheek-pieces being riveted together. The sheave-axle e is also shown. These are all of the 35 members of the tackle-block that are necessary to show in illustrating my riveting device, the parts thus far being lettered the same as in the aforesaid patent.

The parts are assembled and held in place 40 by clamp G during the riveting operation, the clamp fitting accurately the periphery or edge of the tackle-block casing. The clamp is made in two sections, the one section having mortises g at the end, and the other section having engaging tenons g' , with the transverse 45 pins g'' , for holding the members of the clamp together. Before the tackle-block shell is placed in the clamp, blocks H are arranged internally at either end of the shell, such blocks being held firmly in place against the internal metal plate, C', by means of wedge I, 50 interposed between opposing blocks. This wedge has a slot, i , for straddling the axle e .

Blocks H have slight conical depressions h , in which the inner ends of the rivets are upset to form the inner heads of the rivets. The 55 extreme edges h' of blocks H fit it between the body of the cheek-piece and flange a' . Notches h'' are for the passage of the draft-straps, the latter being inserted through notches G' of the clamp after the shell, with blocks H 60 in place, is secured in the clamp. The wedge I engages the ends of the riveting-block at H' , and consequently the one wedge may tighten the four blocks H in case of a single sheave-shell. The wedge is thin enough to allow the 65 draft-straps to pass on either side of it. The clamp is provided with holes G² where the rivets J occur, and a drill (shown in Fig. 1) is provided, a section, L, of the shank of the drill fitting nicely in hole G², by means of 70 which the drill is guided to its place of work. A shoulder, L', by engaging the clamp, forms a stop. The drill proper, l, is just long enough to extend through the flanges of the cheek-pieces and through the inner and outer plates, 75 C and C'. Section l' of the drill cuts a countersink in plates C. Next the rivets are inserted, the inner ends of the rivets resting against blocks H in depressions h . Punch or 80 upset K fits in hole G², the end of the punch having a countersink, k, for forming the outer heads of the rivets. These rivets are usually only about three-eighths of an inch long, and a sharp blow of the hammer is usually sufficient 85 to upset the rivets to form the internal and external heads. After the riveting, pin e is removed, and this releases the draft-straps, which are also removed, after which the clamp may be taken off.

In case of more than one sheave, additional 90 blocks, M, are provided, the edges of which fit between the flanged edges of center-pieces, D, and are wedged apart into the ends of the shell for upsetting the rivets that secure tongs d (see patent aforesaid) to the plates C C'. 95 For each additional sheave additional blocks and wedges I are provided.

It requires some little practice to assemble the parts with dispatch, but with expert workmen a tackle-block may be riveted, including 100 the assembling of the pieces and closing and opening the clamp, in from five to eight minutes.

What I claim is—

1. The combination, with a clamp for embracing the edge of a tackle-block shell of the variety indicated, of blocks adapted to fit internally the ends of the shell where the rivets
- 5 occur, such blocks having depressions for forming the inner heads of the rivets, and one or more wedges for engaging the opposing ends of the blocks for holding the latter in place, substantially as set forth.
- 10 2. The combination, with riveting-blocks and wedges, substantially as indicated, of clamp for embracing the edge of the tackle-block

shell, such clamp being made in detachable sections, and the clamp having holes for inserting the drill and rivets, substantially as set forth.

In testimony whereof I sign this specification, in the presence of two witnesses, this 27th day of February, 1888.

GEORGE A. FORD.
